Inventor:
Walter L. Majors,
By Hugh H. Wagner,
Atty.

UNITED STATES PATENT OFFICE.

WALTER L. MAJORS, OF ST. LOUIS, MISSOURI.

MIMEOGRAPH ATTACHMENT.

1,422,286.

Specification of Letters Patent. Patented July 11, 1922.

Application filed March 31, 1920. Serial No. 370,193.

To all whom it may concern:

Be it known that I, WALTER L. MAJORS, a citizen of the United States, residing in the city of St. Louis, in the State of Missouri, have invented certain new and useful Improvements in Mimeograph Attachments, of which the following is a specification.

This invention relates to mimeographs or the like and can be applied, also, to cylinder printing presses. Its object is to simplify, expedite, and cheapen the printing of any given matter in two or more colors. By this apparatus such printing can always be produced in two or more colors by one operation unless one of the said colors is superimposed upon another.

In the accompanying drawings forming part of this specification, in which like numbers of reference denote like parts wherever they occur,

Figure 1 is a side elevation;

Figure 2 is a top plan view;

Figure 3 is a fragmentary view showing one form of ridge;

Figure 4 is an elevation, showing means for longitudinal adjustment of the printing roll or cylinder, so as to present either a ridge or groove for regulatory purposes, such as hereinbefore described;

Figure 5 illustrates the means of attaching one form of ridges to the printing cylinder or roll;

Figure 6 illustrates non-contact with a ridge; and

Figure 7 illustrates contact with such ridge.

The mimeograph shown in Figure 1 may be of the standard or conventional type in which the legs 1 rest upon the floor. A drawer 2 between them may contain supplies. The machine rests upon the table 3 provided with the hinged leaf 4. The base 5 rests upon table 3 and supports the machine proper. The handle 6 turns on the power, if the machine be a power-driven machine. Otherwise a crank-handle (not shown in the drawings) is used. The dial 7 with pointer 8 can be used if desired to indicate the number printed and to be printed, and to ring a bell (not shown) when the job is finished.

The paper is introduced at the paperfeed 9 and makes its exit into the paper trough 10. Presser 11 causes the paper to feed properly.

The use of regulators 12 and 12' is well understood by mimeograph operators. Inker 13, which is of conventional construction, is adapted to produce internal inking of the mimeograph roll or printing cylinder from the inside.

So far, the description relates only to the well-known mimeograph machine, to which additions are made by the present invention, which can be used without interference in any way with the mimeographs now on the market and, yet, with the added advantages pointed out above.

A bracket or arm 14 is pivoted at 15 to the frame 16 of the machine and supports roll 17 in a revoluble manner. Bracket or arm 18 is pivoted at 19 to the frame 16 of the machine, and supports in a revoluble manner ink roll 20, which is adjacent to inker 21 supported by bracket 22 from arm 18.

Springs 23 and 24 tend to draw rolls 20 and 17, respectively, toward the center roll 25. The said springs 23 and 24 are fastened by eyelets at one end thereof to stud 26 and by hooks 27 to collars 28 at the top of brackets or arms 14 and 18.

It is to be understood that any number of colors desired can be printed by this device, but in the drawings it is illustrated as printing only two colors, the normal or ordinary color applied by inker 13 and a different color by roll 20, which color is received by roll 20 from the inking roll 21, on which the same is preferably first spread and from which it is taken up by roll 20. In use the roller 17 may be provided with an inking roller similar to the inking roller 21 in which case a predetermined portion of the printing drum would be supplied with ink by the roller 17. In this arrangement it will be assumed that the area 29 prints black and the area 30 prints a varying color, such, for instance, as red. An intervening area (not shown in the drawings) could likewise print some other color, or the area 29 may lie between the area 30 and some other area behind area 29, and not shown in the drawings. The arrangements described and mentioned are only illustrations and can be varied at will.

The mimeograph sheet 29 is supplied with ink by the internal inker 13. The printing surface 30 which is provided with any suitable printing means such as type is not sup-

plied with ink by the internal inker 13, but is supplied with ink by reason of its contact with the inking roller 20. Therefore, the roller 20 is necessarily spaced from contact with the surface 29 which, for the purpose of illustration, may be said to be supplied with black ink. Also, the printing surface 30 is necessarily engaged by the roller 20 which, for the purpose of illustration, may be said to be provided with red ink. It is thus apparent that the surface 29 is supplied with black ink and that the surface 30 is provided with red ink so that when the drum 25 is rotated the different colored surfaces 29 and 30 will be engaged with the paper as the paper passes beneath the drum and into the collector 10.

The means employed for spacing the roller 20 from contact with the mimeograph sheet 29 includes one or more arcuate ridges or projections 31 which may be arranged at one or both ends of the drum for contact with a flange or flanges 33 formed at the ends of the inking roller 20. As illustrated in Figure 2 one ridge 31 is located at one end of the printing surface 29 so that when the drum is rotated the ridge 31 will contact with the flange 33 and thereby move the roller 20 outwardly. By reason of this construction the roller 20 which supplies red ink will be spaced from contact at all times with the black mimeograph sheet 29.

The roller 20 is also provided with annular grooves 32 through which another set of blocks forming the ridges 31 may pass. When one set of ridges is so positioned that it passes through the annular groove 32 during the rotation of the drum the roller 20 will not be moved outwardly. Figure 2 illustrates one ridge 31 at one end of the red printing surface 30 and consequently when the printing surface 30 is presented to the roller 20 the two will have contact whereby to ink the surface 30. That is to say, the ridge 31 at the end of the surface 30, does not space the roller 20 from contact with the surface 30. However, the ridge 31 at the end of the surface 30 is employed for spacing the surface 30 from contact with a roller producing a third color in cases where a third color is employed.

Grooves 32 and flanges 33 are preferably continuous, but the ridges 31 are preferably not circumferentially complete around the cylinder or roll 25 but can be made longer or shorter as may be required or desired and may be only one on each end of roll 25 (arranged as shown in Figure 2 to alternate elevation and depression) or there may be a plurality at each end in case it is desired to print in more than two or three colors. The machine, as illustrated in Figure 2 is adapted to print in three colors, with the ordinary mimeograph stencil producing one color and rolls 17 and 20 printing each

a separate additional color. Rolls 17 and 20 may, also, be used to print the same color but different from the main body color produced by the ordinary stencil.

Figure 5 shows how ridges 31 may be composed, that is to say, of blocks 34 having openings 35 therethrough for the passage of tongue 36, which is provided with hook 37 for attachment to the frame 38 of cylinder or roll 25. Spring 39 holds the hook 37 taut against frame 38.

Spring 39 is provided with a hook or the like 43 that fastens to an edge corresponding to edge 38 that is grasped by hook 37. Thus the blocks 34 can be slid or moved anywhere upon tongue 36.

As means for temporarily locking the rolls 17 and 20 on their respective adjusted positions, the bearings or spindles of these several rolls may be and preferably are formed with annular grooves 40 and 41 into which a spring pressed pin 42 may be optionally fitted or engaged.

Standard 44 formed integral with the bracket 14 affords a bearing for shaft 45 that supports either roll 17 or 20, which shaft contains grooves 40 and 41. Pin 42 is fastened in recess 46 in standard 44 and holds the roller 17 or 20 in the groove 40 or 41 to secure the desired position of the roller on its respective shaft.

Having thus described this invention, I hereby reserve the benefit of all changes in form, arrangement, order, or use of parts, as it is evident that many minor changes may be made therein without departing from the spirit of this invention or the scope of the following claims.

I claim:

1. In an apparatus adapted to print in different colors, the combination of a printing member having ridges or projections, and adjoining rolls having depressions and parts projecting relative to the said depressions, the said ridges being composed of individual elements or blocks adapted to vary the same as to length, and a tongue adapted to hold the said elements.

2. In an apparatus adapted to print in different colors, the combination of a printing member having ridges or projections, and adjoining rolls having depressions and parts projecting relative to the said depressions, the said ridges being composed of individual elements or blocks adapted to vary the same as to length, and a tongue adapted to hold the said elements, the said tongue being provided with a hook.

3. In an apparatus adapted to print in different colors, the combination of a printing member having ridges or projections, and adjoining rolls having depressions and parts projecting relative to the said depressions, the said ridges being composed of individual elements or blocks adapted to vary

the same as to length, and a tongue adapted to hold the said elements, the said tongue being provided with a hook and a spring.

4. In an apparatus adapted to print in different colors, the combination of a printing member having ridges or projections, and adjoining rolls having depressions and parts projecting relative to the said depressions, the said ridges being composed of individual elements or blocks adapted to vary the same as to length, and a tongue adapted to hold the said elements, the said tongue being provided with a hook and a spring, and the said spring carrying an additional hook.

5. In an apparatus adapted to print in different colors, the combination of a printing member having ridges or projections, and adjoining rolls having depressions and parts projecting relative to the said depressions, the said ridges being composed of individual elements or blocks adapted to vary the same as to length, and a tongue adapted to hold the said elements, the said tongue being provided with a hook and a spring, the said spring carrying an additional hook, and the said hooks being for attachment to the printing member.

6. In a device of the character described, the combination of a printing member, a roll or rolls in proximity thereto having de-

pressions therein, and projections from the said printing member adapted to be moved into a plurality of positions for alternate engagement with said depressions, the said projections being borne by a tongue or strap secured to the said printing member, and the said tongue being fastened to the said printing member by hooks or the like, and the said hooks being held taut relative to each other by a spring and the undepressed or normal periphery of the said roll or rolls.

7. In a printing apparatus of the character described, the combination of a printing member having projections and a roll or rolls in proximity thereto having depressions and parts higher than the said depressions whereby to move said roll or rolls, alternately, to different positions with relation to such printing member upon their engagement with such projections, and the shaft or shafts of the said roll or rolls having notches therein, and a pin adapted to enter either of the said notches adapted to hold the said roll from sliding movement transversely of the machine but adapted when withdrawn from such notch to permit such movement.

In testimony whereof I hereunto affix my signature.

WALTER L. MAJORS.
